HAIR DRYER

Dieter Rams, Konigstein, Germany, assignor to Braun
Aktiengesellschaft, Frankfurt am Main, Germany

Filed Aug. 31, 1970, Ser. No. 24,785

Claims priority, application Germany Mar. 24, 1970

Term of patent 14 years

Int. Cl. D28—03

U.S. Cl. D86—10

Fig 1

Fig 2

Fig 3

Fig 4

Fig 5

Fig 6

FIG. 1 is a top plan view of a hair dryer showing my new design.

FIG. 2 is a front elevation thereof;

FIG. 3 is an end elevational view;

FIG. 4 is a rear elevational view;

FIG. 5 is an end elevational view similar to FIG. 3, but showing the opposite, far end; and

FIG. 6 is an underside view.

I claim:

The ornamental design for a hair dryer, substantially as shown.
